UNITED STATES PATENT OFFICE.

CHARLES E. HITE, OF PHILADELPHIA, PENNSYLVANIA, ASSIGNOR TO
CHEMICAL POWER COMPANY, A CORPORATION OF DELAWARE.

ROTARY-PISTON ENGINE.

SPECIFICATION forming part of Letters Patent No. 740,979, dated October 6, 1903.

Application filed March 27, 1899. Serial No. 710,583. (No model.)

To all whom it may concern:

Be it known that I, CHARLES E. HITE, a citizen of the United States, residing in the city and county of Philadelphia, in the State of Pennsylvania, have invented certain new and useful Improvements in Rotary-Piston Engines, of which the following is a specification.

My invention relates to the class of motors known as rotary piston engines, which usually comprise, as is well known, a revoluble structure mounted upon a fixed shaft, and embodying a series of radially disposed piston cylinders arranged in equi-distant relationship, in which cylinders are mounted piston heads equipped with piston rods, the converging ends of which latter are connected with or embrace a piston axle eccentric with respect to the point of junction of the axial lines of the piston cylinders and consequently eccentric with respect to the axis of the revoluble body.

Engines of this character are adapted for actuation by various motive fluids, and my improved engine may be driven by a liquefied gas under high pressure.

My improved form of motor shown in the accompanying drawings, however, and herein described, is peculiarly and especially adapted for actuation by carbonic anhydrid or carbon-dioxide, and is of such a character as to render the use of such fluid entirely expedient and practical.

The general form and mode of operation of motors of the class hereinbefore mentioned is well known to those familiar with the art. It is the object of my invention to provide improvements in certain features of construction and in the arrangement of the operative parts of motors or engines belonging to the general class above referred to, whereby their practicability and efficiency are very much enhanced.

In the accompanying drawings I show, and herein I describe, a good form of a convenient embodiment of my invention, the particular subject-matter claimed as novel being herein-after definitely specified.

In the accompanying drawings, Figure 1 is a central, vertical, longitudinal, sectional, elevational, view of a motor embodying my improvements.

Figure 2 is a view in side elevation of the same, partly in section, the section being supposed on the dotted line 2—2 of Figure 1. 55

Figure 3 is a top plan view of the inlet port tripping cams and their carrier plate.

Figure 4 is a transverse, vertical, sectional, elevational, view of a portion of the apparatus, section being supposed on the dotted line 60 4—4 of Figure 1.

Figure 5 is a central, vertical, sectional, transverse, elevational, view of the motor shown in Figure 1, section being supposed on the dotted line 5—5 of said figure. 65

Figure 6 is a vertical, transverse, sectional, elevational, view, section being supposed on the dotted line 6—6 of Figure 1.

Similar letters of reference indicate corresponding parts. 70

In the accompanying drawings,

A B are a pair of vertically disposed standards upon which the operative parts are mounted, the standard B being provided with two independent heads or supporting brackets $b b^2$. 75

C is a horizontal or main shaft, or kindred body, fixedly mounted and supported in the standard A, extending toward the standard B, and provided at its inner end with an elbow C', the outer end of which is provided with what I term a piston axle C², the axis of which piston axle, although out of line with that of the main shaft, is in parallelism with it, as shown particularly in Figure 1. 85

D is the revoluble or piston carrying body of the motor, the same comprising, in the form shown particularly in Figures 2 and 5, a cylindric rim, concentric with respect to the main shaft C,—and three radially disposed piston cylinders D' D² D³ the outer ends of which are merged into or connected with said rim and the inner ends of the shells composing which are secured to each other and open into a central space in which exists the piston axle 95 hereinafter referred to.

A series of radial strengthening webs d are shown as disposed one between each pair of piston cylinders and extending from the rim to the meeting edges of the piston cylinders, 100 to which cylinders said webs are connected, or into the substance of which they merge.

An annular hub D^X, Figure 1, the inner end of which is radially flared, is rigidly connect-

ed as to its flared end to the adjacent face portion of the piston cylinders, and the body of said hub which embodies an opening axial with respect to the revoluble body enclosed and is free for revolution with respect to the main shaft C or an annular bearing plate D⁴ mounted and threaded upon said shaft,—and said hub therefore forms a part of the revoluble body and through it a large portion of the weight of said revoluble body is transmitted to the fixed shaft.

E is a depending yoke provided with a head e mounted and rigidly secured upon the outer end of the piston axle C², and provided as to its other end with a bearing recess e' facing the standard B, and in line with the body of the fixed or main shaft C.

The elbow C' and the yoke E extend in parallelism from the eccentric piston axle to the axis of the revoluble body, the elbow C' being in the form shown integral with the piston axle and the yoke E formed as a separate member but rigidly secured thereto.

The side of the revoluble body adjacent to the standard B is provided in the form of apparatus shown with two axles or bearing members, arranged in alinement, namely an outer, designated F', entered in a suitable bearing in the head b of the standard B, and an inner, F^X, entered in the bearing recess e' in the yoke E.

Said two axles are shown as formed as integrally continuous of each other, and integrally connected with an annular flared collar F. The marginal portion f of said flared collar is rigidly secured to the adjacent portions of the piston cylinders, and said collar with its two supported axles or bearing members, (which collar and axles I may term a spider,) I may form as a separate structure adapted when secured to said revoluble body to revolve with and form a part of it. The axle F^X, and the bearing recess e' of the yoke, form a swivel or journal connection between the yoke which forms an arm of the piston axle, and the revoluble body, at a point axial with respect to the latter.

G' G² G³ are a series of piston heads mounted respectively one in each of the piston cylinders, and adapted to reciprocate therein toward and from the piston axle, and respectively equipped with piston rods g' g² g³ pivotally connected as to their outer ends to said piston heads, and equipped as to their inner ends with apertures by virtue of which they are seated upon the piston axle C², the arrangement being as follows:

The inner end of the piston rod g' is simply a straight shank so to speak; the piston rod g² is as to its lower or inner end formed into two forks or branches, and the piston rod g³ is likewise provided with or formed into two forks or branches.

The forks of the piston rod g² are closer together than the forks of the piston-rod g³, so as to be adapted to lie or exist between the forks of said rod g³, as shown in Figure 1, and

the space between the forks of said piston rod g² is of such size as to receive the unforked inner end of the piston rod g'.

The nested arrangement described maintains the meeting inner ends of the piston rods in such relationship to each other that they will rotate easily and smoothly and not bind upon each other or the piston axle.

In the operation of the herein described device, as will be understood, the shaft C with its elbow and piston axle, and the yoke carried by said piston axle, remain stationary, while the rim, the piston chambers, the hub D^X, and the two axles F' and F^X, all revolve together upon an axis which is that of the fixed shaft C.

In the operation of the motor, as the revoluble structure rotates, each piston head as it reaches about the position with relation to the piston axle occupied by the piston head G' in the drawings, will be, as shown, in the outer or distant end of its piston cylinder, and quite close to the rim or periphery of the revoluble structure, while, in the continued rotation of the motor, owing to the eccentricity of said piston axle with respect to the revolving structure, said piston heads move inward to the vicinity of the inner end portions of their respective cylinders.

Motors of this type are operated by introducing behind the pistons, about the time, or immediately after, they successively reach the outer ends of their respective strokes, motive fluid, which, expanding or exerting pressure in such position, compels the rotation of the revoluble structure in a manner well understood, provision being made for the exhaustion of said fluid from the several chambers about the time the pistons have successively reached or passed the point in the revolution of the structure at which they are farthest from the rim of the revoluble structure.

The means which I prefer to employ for the supply of motive fluid to the several piston chambers or cylinders, at the time they successively reach the appropriate point in the movement of the revoluble body, are as follows:

H is a fluid inlet pipe, (see Figure 1,) the inner end of which is passed into a countersunk axial recess K formed in the axial member F', which recess is formed or provided at its inner end with three radial outlet branches designated k'.

Within the countersunk portion of the recess K and about the exterior of the pipe H is seated a quantity of packing material K' compressed and held in position by an annular nut K² threaded into the outer portion of said recess and encircling the pipe H.

The inner end of the pipe H is slightly reduced in diameter, so that a small gas-chamber h is formed at the inner end of the recess.

A series of radial branches h' lead from the bore of the pipe H and discharge into said gas-chamber so that the gas passing through

said pipe enters said chamber and passes out through the outlet branches k' referred to.

5 J are a series of three radially disposed pipes the respective inner ends of which are entered in countersinks formed in the outer ends of the passages or outlets k' , and the outer ends of which lead to and discharge respectively into three inlet valve chambers L conveniently formed in the hollow interiors 10 of shells L^x mounted respectively on the sides of the three piston chambers.

15 L' are a series of angular inlet ports, three in number, leading respectively each from one of the valve chambers L to the outer portion 20 of one of the piston chambers, and each embodying a seat for an inlet puppet valve M mounted in the valve chamber with which said port is in communication.

25 The outer portion of the hollow interior of each of the shells L^x is closed by packing material of any preferred character, inclosed between a pair of annular plates the outer of which is in threaded engagement with its shell, and through which projects the stem 30 M^x of the valve mounted in the valve chamber at the inner end of said shell.

35 The lower or inner ends of said valve stems M^x are provided each with a circumscribing groove, as shown particularly in Figure 1.

40 P is a bell crank lever, hereinafter termed the inlet tripping lever, pivotally supported in a lug or ear secured to an adjacent portion of the revoluble structure, the inner end of which inlet tripping lever is engaged 45 in the annular groove in the valve stem M^x , and the outer end of which projects outward and in position to be tripped by one of a pair, $P^2 P^3$, of inlet tripping cams, erected upon a cam carrier plate P^4 adjustably mounted on 50 a collar P^5 fixedly but adjustably mounted on the exterior of the head b of the standard B .

55 One of said inlet tripping levers P is, in the apparatus depicted, employed in connection with each of the inlet valves, and said levers, as will be understood, in the operation of the apparatus, successively encounter and are tripped by the inlet tripping cam which happens to be set in operative position, whereby 60 the timely unseating of the successive valves is occasioned.

65 The collar P^5 which embraces and is supported as stated by the head b of the standard B , is adapted to have movement in the direction of the axis of the pipe H upon said head b , and the carrier-plate P^4 is supported in a countersunk circumscribing groove or recess formed in the outer face of said collar.

70 The carrier plate P^4 is adapted to be maintained in a fixed position with relation to said collar by a stud P^6 passing through its structure and adapted to engage in any one of a series of recesses P^7 (see Figure 4) formed in the bottom of the undercut or countersunk groove, said stud passing through a recess P^8 closed by a cap P^9 , a spring within which recess bears against said cap and against a suit-

able collar on said stud, and maintains said stud temporarily in engagement with any recess P^7 in which it happens to be inserted. 75

In the operation of my apparatus, therefore, as in the rotation of the revoluble structure one after the other of the piston cylinders in succession reaches the appropriate point, *i. e.*, about the position occupied by 75 the piston cylinder D' in Figures 1 and 5, the inlet tripping levers associated with the respective piston cylinders will be tripped by encountering that one of the pair of cams $P^2 P^3$ which happens to be in operative position 80 and tripped or deflected by such cam their inner ends when drawn downward carrying with them the valve stems M^x and valves M , and giving the lead to the gas contained in the adjacent pipes J , through the inlet ports 85 to the piston chambers, the valves each remaining open of course during the period the inlet tripping lever is riding over the cam, which is, of course, to be of any preferred length. 90

The acting free ends of the so-called tripping cams P^2 and P^3 , are in the embodiment of my invention shown in the drawings of such narrow extent, circumferentially of the structure, that they are mere studs or trips 95 and serve to occasion an unseating of the valves of very brief duration, and the word "cam" as employed herein in connection with the devices $P^2 P^3$ is intended to cover devices of kindred character whether cams strictly as 100 such or trips or studs.

105 As a result of this arrangement, the gas is automatically supplied to the several piston chambers in succession as they reach that predetermined point of their revolution at which the entrance of the gas is most advantageous.

110 The point at which the inlet tripping levers and consequently the inlet valves are operated, is, of course, determined by the position of the inlet tripping cam, which happens to be in operative position, *i. e.*, in position to be encountered by the inlet tripping levers.

115 As the gas pipe H is stationary while the axle in which it is entered is revoluble, it becomes necessary to very firmly brace the outer end of said pipe, and this I conveniently accomplish by providing it intermediately of its length with a valve-provided elbow H^2 to 120 which the respective sections of the pipe H are connected in any preferred manner, and I support said elbow and pipe in or upon two distinct divisions or branches of the head b^2 of the standard B , as shown in Figure 1. 125

130 The arrangement I provide to exhaust the gas from the several piston chambers is as follows:

Q are a series of outlet ports, three in number, leading respectively from the respective piston chambers to a series of valve chambers Q' , each embodying a valve seat. Said chambers and seats constitute of course continuations of the outlet ports or passages.

Q² are a series of outlet valves, mounted in said valve chambers and adapted to said seats, and each equipped with a valve stem Q³.

Q⁴ are valve stem casings inclosing said valve stems, and q are spiral springs mounted in said valve stem casings, and each bearing as to one extremity against the structure of the casing, and as to the other against a collar q' mounted on the valve stem.

10 As a result of this arrangement the springs operate to normally maintain the outlet valves snugly in their seats and the outlets from the piston chambers consequently closed.

15 In the set of the parts illustrated in Figure 1, the valve M of the inlet port of the cylinder D' is as shown, in closed position, and the valve Q² of the outlet port of said cylinder in open position; the path taken by the 20 motive fluid escaping past the collar on the stem of said last mentioned valve being indicated by arrows. In said position of parts shown in Figure 1, the outlet tripping lever R is on and about to pass from the upper 25 end or corner of the outlet tripping cam R², which end is indicated in dotted lines.

30 R are a series of outlet tripping levers, three in number, each pivotally connected to the side of a piston cylinder in line beneath the stem of one of the outlet valves, and each as to its outer end adapted to encounter, ride upon, and be tripped by, the crest of one of a pair of outlet tripping cams R' R².

35 Cams R' R², which I term outlet tripping cams, each extend somewhat more than half the distance around the fixed shaft C,—but are disposed at opposite sides thereof, slightly overlapping at their lower extremities,—are as to their respective ends, secured to a collar R^X mounted upon the head of the standard A, and which collar is free for adjustment longitudinally of said head to carry either of said outlet tripping cams to a position in line beneath the series of outlet tripping levers.

45 The form, disposition, and timing, of the outlet tripping cam encountered is such that each outlet tripping lever encounters and rides along it after the piston in connection with which such tripping lever operates has reached approximately the innermost point of its stroke, with the result that each outlet tripping lever will at the appropriate time elevate its associated outlet valve stem and valve, so as to give the lead to the exhaust from the piston chamber in connection with which such lever stem and valve operate.

50 The outlet tripping cam which is in operative position with respect to the outlet tripping levers maintains through the outlet tripping levers and the valve stems the respective outlet valves as they successively pass over said cam, elevated and open, until in the 60 revolution of the parts the successive pistons 65 return nearly or quite to what may be termed their first position, that is to say, the position occupied by the piston G' in Figure 1.

Preferably the outer ends both of the inlet tripping levers and the outlet tripping levers, make contact with their respective cams 70 through an interposed caster-like arrangement consisting of balls or spheres mounted in suitable spherical recesses in the under faces of said levers.

75 A valve stem M^X and its associated inlet tripping lever P, constitute, in the particular embodiment of my invention illustrated, what may be termed a valve gear or operating mechanism of an inlet valve M, that is to say, the mechanism through which an inlet tripping cam acts to unseat one of said valves. Similarly, a valve stem Q³ and its associated outlet tripping lever R constitute, in said embodiment, what may be termed a valve gear or operating mechanism of an outlet 85 valve Q². Manifestly, however, in other embodiments of my invention, the valve gears may be altered and varied in the form and arrangement or increased or lessened in the 90 number of their constituent parts without departure from the spirit of my invention. I do not restrict myself to the use, for example, of the inlet and outlet tripping levers.

95 T is a throw rod running along the base of the machine, disposed in suitable supporting sockets, and provided with a pair of arms t¹ t² rigidly secured to the respective collars P⁵ and R^X.

100 t^X is a link by which one end of said rod is connected to a pivoted lever T^X, by the manual movement of which said throw rod may be shifted to move said collars P⁵ and R^X longitudinally, to carry the cams P³ and R²,—or the cams P² and R',—within range of action of the inlet and outlet tripping levers P and R. 105

110 The cams P² P³, as shown particularly in Figures 2, 3, and 4, of the drawings, are oppositely disposed, on the carrier P⁴, that is to say, are separated a distance, longitudinally of the axis of the apparatus, corresponding to the distance by which the two 115 cams R' R² are separated, and are also separated a short distance circumferentially of the apparatus. The inlet tripping cam P³ and the outlet tripping cam R², act in concert upon the inlet tripping levers and the outlet tripping levers, in one set of the parts,—

120 and the inlet tripping cam P² and the outlet tripping cam R' act in concert upon the inlet tripping levers and the outlet tripping levers in the other set of the parts. If the motive fluid enters the successive cylinders when the cams P³ R² are in operative position, as shown in the drawings, the revoluble body 125 will rotate in the direction of the arrows in Figures 2 and 5, while if said motive fluid enters the successive cylinders when the cams P² R' are in operative position, the revoluble body will be caused to rotate in the opposite direction. The movement of the rod T is sufficient to carry the respective pairs of cams from one position to the other.

130 Referring to the position of the parts illustrated, the cam P³ will occasion the tripping

or unseating of the inlet valves of the respective cylinders to admit motive fluid just after each cylinder has passed the position occupied by the cylinder D' in Figure 5, that is to say, just after the piston head of such cylinder has reached the limit of its outward stroke, and such motive fluid acting against the successive piston heads operates to drive the revoluble body to the right, that is to say, in the direction of the arrows of Figures 2 and 5.

When, however, upon the throw of the rod T,—the revoluble body being supposed to be rotating to the right,—the cams P³ R² are thrown out of operative position, and the cams P² R' thrown into operative position, said cam P² (being, as shown, at some little distance, circumferentially of the apparatus, from the cam P³) will unseat the inlet valve of the first cylinder coming toward it just before said cylinder reaches the position occupied by the cylinder D' in Figure 5, and before the piston head in such cylinder reaches the outer limit of its stroke, and the consequent inrush to the outer end of said cylinder of the gas or motive fluid will cause the stoppage and return of said piston head to the inner end of its cylinder, and the consequent rotation of the revoluble body to the left.

Assuming the cylinder first to receive motive fluid after the shifting of the cams, to be that designated D', and that said cylinder, at the time of receiving such fluid, occupied a position a little to the left of that it is in Figure 5 shown as occupying, it is manifest that the action of the motive fluid in said cylinder D' will not be actively opposed by the motive fluid in either of the other cylinders. This for the reason that, under the actuation of the outlet cam R², the outlet valve of cylinder D² has by the time the said cylinder has nearly reached the position it is shown in Figure 5 as occupying, been, in the travel of the revoluble body in the direction of the arrow, open for a brief time, so that a part of the motive fluid of the cylinder D² has escaped. Furthermore, the set of the parts is now such that in the travel of the revoluble body opposite to the direction of the arrow, the outlet valve of said cylinder D² will quickly (through, of course, in the arrangement illustrated, its stem and its associated outlet tripping lever), encounter the outlet cam R' and the motive fluid will be altogether exhausted from said cylinder. While at the beginning of said reverse movement of the revoluble body the outer end of the cylinder D³ will be full of motive fluid, such fluid will, in the travel of the revoluble body in a direction the opposite of that of the arrow, be exhausted from said cylinder, for the reason that in the new or reversed set of the parts its outlet valve will be opened and held open through the agency of the cam R', until said valve in its travel to the left passes away from said cam.

The collar P⁵ is, as shown in Figure 4, secured to the cylindric head by set screws; the

inner ends of these screws work in grooves in said head, which grooves are in parallelism with the adjacent portion of the pipe H, 70 and, therefore, do not happen to be visible in any of the figures of the drawings. In the longitudinal shifting of said collar, said screws travel, along said grooves.

V is an oil passage leading through the 75 central portion of the shaft C, its elbow, and the piston axle, and provided with a series of outlets v through the substance of the piston axle into a spiral recess in the face of said axle.

V^X is an oil cup provided with an oil pipe v' the inner end of which is entered in said passage V.

Oil supplied to said oil cup V^X will consequently be constantly supplied, through the 85 passages described, to the exterior of the piston axle, and maintain the nested ends of the piston rods in a thoroughly lubricated condition.

W, Figures 1 and 5, are a series of three oil 90 cups, mounted upon the revoluble structure in adjacency to its hub, and each provided with an outlet pipe w leading to and opening through the wall of one of the piston chambers.

w' are inlet pipes, leading into said cups, 95 and each closed by any suitable valve.

When the structure is rapidly rotated the oil in said cups will, under the centrifugal force developed, be fed outwardly through 100 the pipes w and gradually discharged upon the inner faces of the walls of the piston chambers with the result that the said walls will be maintained in a thoroughly lubricated condition and the smooth and frictionless 105 working of the pistons insured.

My improved engine may be employed in any capacity in which motors are useful.

I contemplate in practice to bend a belt about the periphery of the revoluble structure and connect said belt with any mechanism it may be desired to propel.

The words, "gas", and "motive fluid" in the claims are employed as generic terms, and intended to cover broadly all available 115 forms of motive gases, fluids or vapors.

Having thus described my invention, I claim and desire to secure by Letters Patent—

1. In a rotary piston cylinder engine, in 120 combination, a body provided with a plurality of radially disposed piston cylinders, a shaft concentric with respect to said body and extending into its interior, a piston axle connected to said shaft and arranged within said 125 revoluble body in a position eccentric with respect to it, piston heads disposed within the respective cylinders, connections between said heads and the piston axle, gas passages leading from the central portion of the body 130 to the respective cylinders, valves mounted on said body and arranged to control said respective passages, gears, one of which is associated with each of said valves, and shiftable

means by which said valves may all be successively unseated either at one or the other, according to the position of such means, of two selected regions occupying different positions relatively to the axis of said shaft.

2. In a rotary piston cylinder engine, in combination, a revoluble body having a series of radially disposed piston cylinders, a non-rotating shaft axial with respect to said body and extending to its interior, an eccentric piston axle carried on said shaft, pistons mounted in the cylinders, connections between the pistons and the piston axle, a non-rotating motive fluid supply pipe, passages formed in the revoluble structure leading from said supply pipe to the respective cylinders and discharging therein, inlet valves which control said passages, outlets formed in the respective cylinders, valves which control said outlets, gears connected with the respective valves, two inlet valve tripping cams arranged at a distance apart circumferentially of the apparatus, two outlet valve tripping cams, occupying different positions circumferentially of the axis of the revoluble body, one inlet valve tripping cam and one outlet valve tripping cam forming an operative set of cams adapted to occasion the operation of said inlet valves and outlet valves, respectively,—the other inlet valve tripping cam and the other outlet valve tripping cam forming a second operative set adapted to occasion the operation of said inlet and outlet valves, respectively, said two sets of cams being adapted to be shifted alternately into acting relation with the inlet and outlet valves, substantially as set forth.

3. In a rotary piston cylinder engine, in combination, a fixed shaft, a standard in which said shaft is mounted, a piston axle carried by said fixed shaft, a revoluble body mounted on said fixed shaft and embodying radial piston cylinders, pistons deposited on the respective cylinders and connected with the piston axle, a depending yoke carried by the piston axle, a spider secured to and rotating with said revoluble body, and having its bearing in said depending yoke and in a standard, and means for supplying gas to and exhausting it from the piston cylinders, substantially as set forth.

4. In a rotary piston cylinder engine, in combination, a standard or support, a non-rotating shaft mounted on said support, an eccentric piston axle mounted on said shaft, a revoluble body provided with a hub having a bearing on said fixed shaft, a second standard or support, embodying a fixed bearing, an axle mounted on said revoluble body and rotatable with it and entered in said fixed bearing, piston cylinders carried by said revoluble body, pistons mounted in said cylinders, connections between said pistons and the piston axle, an axial passage formed in the rotating axle of the revoluble body which passage embodies a cylindric enlargement, a fixed gas supply pipe entered and extending

through said axial passage and discharging therein, packing disposed in the enlargement of the axial gas passage and encircling the gas supply pipe, a nut or plug encircling the gas supply pipe, mounted and secured within the axial passage, and compressing said packing therein, and means for conducting gas from said passage to the several cylinders, substantially as set forth.

5. In a rotary piston cylinder engine, in combination, a standard or support, a non-rotating shaft mounted on said support, an eccentric piston axle mounted on said shaft, a fixed yoke carried by said eccentric piston axle a revoluble body provided with a hub having its bearing on said shaft, a second standard or support provided with a fixed bearing, an axle mounted on said revoluble body and rotating with it, and entered as to one end in said fixed bearing and as to its other end in said yoke, piston cylinders, carried by said revoluble body, pistons mounted in said cylinders, connections between said pistons and the piston axle, and means for supplying gas to and exhausting it from the piston cylinders, substantially as set forth.

6. In a rotary piston cylinder engine, in combination, a support or standard, a non-rotating shaft mounted on said support, an eccentric piston axle mounted on said shaft, a fixed yoke carried by said eccentric piston axle, a revoluble body provided with a hub having its bearing on said shaft, a second standard or support provided with a fixed bearing, an axle mounted on said revoluble body and rotating with it, entered as to one end in said fixed bearing and as to its other end in said yoke, piston cylinders carried by said revoluble body, pistons mounted in said cylinders, connections between said pistons and the piston axle, an axial gas passage formed in the axle mounted on the revoluble body and equipped with branches extending radially therefrom through the substance of the axle, means for supplying gas to said passage, means for conveying gas from said radial branches to the several cylinders, and means for exhausting the gas at the appropriate times from the several cylinders, substantially as set forth.

7. In a rotary piston cylinder engine, in combination, two fixed standards, a non-rotating shaft supported on one of said standards, a revoluble body having a hub encircling and rotating upon said non-rotating shaft, and having also an axle entered and rotating in a horizontal bearing on the other standard, an eccentric piston axle mounted on the said non-rotating shaft, a non-rotating yoke carried by said piston axle, a projection on the rotating axle having a bearing on said yoke, a gas passage formed in said rotating axle, a series of piston cylinders embodied in said revoluble body, pistons mounted in said cylinders, connections between said pistons and said piston axle, means for supplying gas from the gas passage to the respective cylinders.

ders, and means for automatically exhausting gas from said cylinders, substantially as set forth.

8. In a rotary piston cylinder engine provided with a series of piston chambers having inlet valves adapted to be tripped by inlet tripping levers, in combination, a head, a collar mounted on said head and adapted to be moved lengthwise of the same, a cam carrier plate mounted on said collar and adapted to be moved circumferentially of the same and secured in various positions, and cams mounted on said cam carrier plate and adapted to be encountered by the inlet tripping levers, substantially as set forth.

9. In a rotary piston cylinder engine provided with a series of piston chambers having inlet valves adapted to be tripped by inlet tripping levers, in combination, a head, a collar mounted on said head and adapted to be moved lengthwise of the same, a cam carrier plate mounted on said collar and adapted to be moved circumferentially of the same and secured in various positions, and a pair of inlet tripping cams mounted on said plate at a distance apart from each other circumferentially of the collar and at a distance from each other longitudinally of the axis of the head.

10. In a rotary piston cylinder engine, as a means for tripping an inlet tripping lever, a head, a collar mounted on said head and adapted to be moved lengthwise of the same, a cam carrier plate mounted in an undercut groove in the face of said collar, and provided with a stud adapted to engage in recesses in the face of the same, a spring which tends to normally maintain the said stud in engagement with one of said recesses, and a pair of cams arranged at a distance from each other circumferentially of the collar, mounted on said cam carrier plate, substantially as set forth.

11. In a rotary piston cylinder engine, in combination, a fixed shaft, a piston axle, a revoluble body mounted on said fixed shaft and having piston cylinders, pistons, and piston rods, a trunnion like axle carried by and rotating with said revoluble body and embodying an axial gas passage, a gas pipe leading to the interior of said gas passage, a series of inlet ports formed one in connection with each of the cylinders, a series of pipes leading from the gas passage or branches thereof to said inlet ports, valve chambers formed one in connection with each of said inlet ports, puppet valves mounted one in each of said valve chambers, stems connected to said puppet valves and protruding through suitable packed openings formed in the walls or adjacent portions of the valve chambers, and means for tripping or operating all said valves at a predetermined point in each rotation of the structure, substantially as set forth.

12. In a rotary piston cylinder engine, in combination, a fixed shaft, a piston axle, a revoluble body mounted on said fixed shaft and having radial piston cylinders containing pis-

tons and piston rods, a series of valve provided inlet ports leading to the respective cylinders and in communication with a source of gas supply, a series of outlet ports formed in said revoluble body, and in communication with the respective piston cylinders, valves which control said outlet ports, independent of the valves which control the inlet ports, stems depending from said outlet valves, a series of tripping levers mounted on and carried by the revoluble structure the throw of which occasions the unseating of the outlet valves, a pair of cams arranged on opposite sides of the fixed shaft, adapted to be alternately carried into position to be encountered by said outlet tripping levers, substantially as set forth.

13. In a rotary piston cylinder engine, a revoluble structure embodying radial piston chambers each equipped with a valve provided inlet port on one side and a valve provided outlet port on the other, a fixed shaft, a piston axle eccentric with respect thereto, pistons disposed in the respective piston chambers and connected with the piston axle a series of inlet tripping levers, a series of outlet tripping levers, a pair of cams arranged at a distance from each other both in the direction of the axis of the revoluble structure and circumferentially of said axis, supported in the vicinity of the inlet tripping levers, a pair of cams respectively arranged on opposite sides of the fixed shaft, supported in the vicinity of the outlet tripping levers, and means for occasioning the concerted movement of the cam supporting devices to carry selected cams, one of each pair, into position to trip said inlet and outlet tripping levers, respectively, substantially as set forth.

14. In a rotary piston cylinder engine, a revoluble structure embodying radial piston cylinders, pistons and piston rods mounted in said cylinders, a fixed shaft, a piston axle eccentric with respect thereto, each cylinder having in one side an inlet port equipped with an inlet valve and in the other side an outlet port equipped with an outlet valve, a pair of cams arranged at a distance from each other circumferentially of the axis of the revoluble structure, mounted on a longitudinally moving collar or device in the vicinity of the inlet valves, a pair of cams arranged on opposite sides of the fixed shaft and mounted on a longitudinally movable collar or device in the vicinity of the outlet valves, devices through which said valves make contact with the respective cams, a longitudinally movable rod mounted in a suitable bearing and connected to said movable devices or collars, and a manually operated device to occasion the longitudinal movement of said rod, substantially as set forth.

15. In a rotary piston cylinder engine, a support provided with a bearing, a revoluble body formed with an axial opening at one side, and at its opposite side provided with a hollow axle journaled in said bearing, a main

- shaft, an eccentric piston axle carried on said shaft, a member extending from the end of the piston axle to a point opposite the axis of said main shaft, the end of said member being journaled or swiveled with respect to one side of the revoluble body, and the main shaft being extended through said axial opening in the body and secured against rotation, a plurality of cylinders carried by said body and provided with pistons connected to the eccentric piston axle, the hollow axle being closed at its inner end, a connection from said hollow axle to the cylinders, and means for supplying motive fluid to said hollow axle, substantially as set forth.
16. In a rotary piston cylinder engine, a supporting frame, a revoluble body formed with an axial opening at one side and at its opposite side provided with a hollow axle, adapted to receive motive fluid, said hollow axle being journaled in a bearing formed in said supporting frame, a motive fluid conveyer arranged to discharge within said fluid receiving hollow axle, a fixed shaft, provided with an eccentric piston axle, said shaft being extended through said axial opening and suitably supported and a plurality of cylinders carried by said body and provided with pistons connected by pitmen to said piston axle, connections from the fluid receiving hollow axle to the cylinders, valves which control said connections, a cam adapted to trip said valves, sta-

tionary relatively to the revoluble body, but adapted to be set to and secured in various positions of adjustment circumferentially of the axis of the revoluble body, substantially as set forth.

17. In a rotary piston cylinder engine, in combination, a body provided with a plurality of radially disposed piston cylinders, each having an outlet controlled by an outlet valve, a shaft central with respect to said body and extending into its interior, a piston axle connected to said shaft and arranged within said revoluble body in a position eccentric with respect to it, piston heads disposed within the respective cylinders, connections between said heads and the piston axle, supply passages leading from the central portion of the body to the respective cylinders, inlet valves mounted on said body and arranged to control said respective passages, an inlet tripping cam adapted to successively unseat the inlet valves, and another cam adapted to successively unseat the outlet valves, substantially as set forth.

In testimony that I claim the foregoing as my invention I have hereunto signed my name this 16th day of March, A. D. 1899.

CHARLES E. HITE.
